UNITED STATES PATENT OFFICE.

JOHN L. SOMMER, OF NEWARK, NEW JERSEY.

DESIGN FOR A HANDLE FOR ICE-PICKS.

45,499.

Specification for Design.

Patented Mar. 24, 1914.

Application filed August 28, 1913. Serial No. 787,212. Term of patent 14 years.

To all whom it may concern:

Be it known that I, JOHN L. SOMMER, a citizen of the United States, residing at Newark, county of Essex, and State of New Jersey, have invented a new, original, and ornamental Design for Handles for Ice-Picks, of which the following is a specification, reference being had to the accompanying drawing, forming part thereof.

Figure 1 is a side view of my new handle

for ice-picks. Fig. 2 is a perspective view of the same and Fig. 3 is an end view.

I claim:

The ornamental design for a handle for ice-picks, as shown.

JOHN L. SOMMER.

Witnesses:

J. G. COLEMAN,

W. V. COLEMAN.
